(57) **CLAIM**

The ornamental design for a display screen with animated graphical user interface, as shown and described.

DESCRIPTION

FIG. 1 is a front view of a display screen with animated graphical user interface showing a first image of our new design; and,

FIG. 2 is a front view of a second image thereof.

The appearance of an image sequentially transitions to another between FIG. 1 and FIG. 2. The process or period in which an image transitions to another forms no part of the claimed design.

The outer peripheral solid lines in the figures show a display screen. The evenly spaced broken lines that depict letters, numbers, a human upper body in the icon at the upper right corner of the image in FIG. 1 and FIG. 2, and a pattern on a shoe in the icon shown in the graph portion of the image in FIG. 1 form no part of the claimed design.

The dotted line graph feature in FIGS. 1 and 2 forms part of the claimed design as shown.
